UNITED STATES PATENT OFFICE.

EMILE HARDY, OF NEW YORK, N. Y., ASSIGNOR TO ANDREW H. HOAG,
OF SAME PLACE.

DESIGN FOR A CLOCK-CASE.

SPECIFICATION forming part of Design No. 31,227, dated July 18, 1899.

Application filed June 13, 1899. Serial No. 720,413. Term of patent 31 years.

To all whom it may concern:

Be it known that I, EMILE HARDY, a citizen of France, residing at New York, in the county and State of New York, have invented and 5 produced a new and original Design for a Clock-Case, of which the following is a specification, reference being had to the accompanying drawing, forming part thereof and illustrating in front elevation a clock-case 10 bearing and incorporating my design.

The leading feature of my design consists of the form and ornamental character of the clock-case, substantially as shown in the drawing.

15 In the drawing, A designates the clock-case as a whole, said case comprising the central ornamental band B, the ornate leg-supports

C C, the representation of a human figure D above said central band B, the conventionalized scroll figures E E at the sides of the 20 said band B, the floral representations F, and the festoon floral representations G, the whole being substantially as illustrated.

What I claim is—

The design for a clock-case, substantially 25 as shown and described.

Signed at New York, in the county and State of New York, this 10th day of June, A. D. 1899.

EMILE HARDY.
